Primary Examiner — Karen E Kearney

(74) *Attorney, Agent, or Firm* — Wong, Cabello, Lutsch, Rutherford & Bruculeri, LLP.

(57) **CLAIM**

The ornamental design for a card with symbols, as shown and described.

DESCRIPTION

The FIGURE is a top plan view of a card with symbols, showing our new design.

The broken line showing in the FIGURE is for the purpose of illustrating environmental structure and forms no part of the claimed design.

1 Claim, 1 Drawing Sheet
